(57) **CLAIM**

The ornamental design for an operation panel for a digital copying machine, as shown and described.

DESCRIPTION

FIG. 1 is a front elevation of an operation panel for a digital copying machine according to the present invention;

FIG. 2 is a rear elevation thereof;

FIG. 3 is a top plan view thereof;

FIG. 4 is a bottom plan view thereof;

FIG. 5 is a right side elevation thereof;

FIG. 6 is a left side elevation thereof;

FIG. 7 is a top, front and right side perspective view thereof; and,

FIG. 8 is a top, front and left side perspective view thereof.
